UNITED STATES PATENT OFFICE.

ALBERT W. LAWNIN, OF ST. LOUIS, MISSOURI, ASSIGNOR OF ONE-HALF TO LOUIS W. LAWNIN, OF EDWARDSVILLE, ILLINOIS.

LIQUID-SOAP DISPENSER.

1,103,521.

Specification of Letters Patent.

Patented July 14, 1914.

Application filed October 8, 1913. Serial No. 793,141.

To all whom it may concern:

Be it known that I, ALBERT W. LAWNIN, a citizen of the United States of America, and a resident of the city of St. Louis and 5 State of Missouri, have invented certain new and useful Improvements in Liquid-Soap Dispensers, of which the following is a full, clear, and exact description, reference being had to the accompanying drawings, forming 10 a part of this specification.

My invention relates to a liquid soap dispenser, comprising an air tight reservoir, and a valve by which liquid soap may be drawn in measured quantities from said reservoir, the said valve providing for the admission of air into the air tight reservoir at 15 each soap dispensing operation.

Figure I is a view, partly in elevation, and partly in vertical section, of the lower 20 end of my soap dispenser. Fig. II is a bottom view of the discharge members of my dispenser. Fig. III is an enlarged section through the discharge members. Fig. IV is a view of the valve washer. Fig. V is a 25 cross section taken on line V—V, Fig. I.

In the drawings: 1 designates the reservoir of my soap dispenser. At the lower 30 end of said reservoir is a discharge nozzle arranged at an angle to the vertical axis of the reservoir. The discharge nozzle comprises neck 2, which merges into a valve housing 4, and a spout 3 extending from said valve housing in alignment with said neck 2. The duct in the neck 2 and the duct 35 in the spout 3 are both of vertically elongated shape, as seen most clearly in Fig. V, the elongation of these ducts being continued throughout the lengths of the ducts for a purpose to be hereinafter explained.

Within the valve housing 4, interposed between the spout 3 and neck 2 of the discharge nozzle, is an annular valve seat 5, which receives the body 6 of a dispensing 40 plug valve, by which the contents of the reservoir 1 is dispensed, and air is admitted to the air tight reservoir to overcome the presence of a vacuum therein. The dispensing valve is provided with a handle 7, by which it is operated, and in the body of the 45 valve are pockets 8 which, upon the operation of the valve, are brought consecutively into registration with the elongated duct in the neck 2 and in the spout 3. The pockets 8 are elongated vertically or longitudinally of 50 the valve body 6, and each pocket is of a

length or height corresponding to the height of the ducts with which it registers, as stated.

The dispensing valve 6 is provided at its lower end with an extension 9 containing an annular groove 10. This extension receives a spring washer 11, by which the plug valve is yieldingly held in the valve seat 5 provided therefor, the washer containing a key hole slot 12, in 60 which the grooved extension of the valve is seated, and being provided with tongues 11', which rest against the lower face of the spout 2 around the valve seat 5.

In the practical use of my soap dispenser, 70 the operation is as follows: Air enters the duct in the spout 3 of the discharge nozzle and when any pocket 8 in the dispensing valve is brought into registration with the duct in said spout, said pocket is filled with 75 air, and upon the dispensing valve being rotated in the valve seat 5 provided therefor, the air in the pocket becomes confined therein between the walls of the pocket and the wall of said valve seat. This air is carried 80 in the pocket until the pocket is brought into registration with the vertically elongated duct in the neck leading from the reservoir 1, when the air escapes from the pocket at the upper end of the latter and passes into the duct at the top of the liquid 85 contents therein, and from said duct to the body of the reservoir, rising eventually to the surface of the liquid contents of the reservoir. The air thus admitted overcomes 90 any tendency to the existence of a vacuum in the reservoir 1 and the neck 2 of the discharge nozzle, and the liquid contents in said duct enters into the pocket in registration 95 with said duct whereby the latter is supplied with contents ready to be delivered to the spout 3. A further operation of the dispensing valve to the necessary degree causes the pocket supplied with liquid contents to be brought into registration with the vertically elongated duct in the spout 3 of the discharge nozzle, in order that said liquid contents may be discharged into and 100 through the spout. Immediately upon the pocket being brought into such registration, the liquid contents of the pocket commences 105 to flow from the pocket by moving downwardly therein and toward the bottom wall of the duct in the spout, and the flow of the liquid in this direction leaves the upper por- 110

tion of the vertically elongated duct in the spout occupied only by air and, as a consequence, the air therein and air entering the spout to a further degree is permitted to 5 press against the escaping liquid, with the result that such liquid is quickly and positively emptied from the dispensing pocket and from the duct in the discharge spout.

My dispenser is constructed in the manner 10 described to render it efficient in dispensing liquid soap, or other liquids, from which bubbles are formed when air is brought into contact therewith, and one of the main advantages in the elongated ducts in the 15 neck 2 and discharge spout 3 and the elongated pockets in the dispensing valve of my dispenser lies in the fact that by the production of the elongated passageways and elongated receptacles in the valve, I eliminate 20 possibility of interference with the flow of the liquid, due to the presence of bubbles. It will be apparent that in the event that bubbles should be formed, either in the duct in 25 the neck 2 or in or at the end of the duct in the spout 3, these bubbles being of globular form cannot, within their radius, wholly obstruct the vertically elongated duct in which they are located, or which they span; and, consequently, air may readily pass 30 them to perform its function in providing for the desired flow of liquid through the duct partially obstructed by the bubble.

While I have described my dispenser as 35 being used particularly for dispensing liquid soap it is obvious it might be employed for

dispensing other liquids. I, therefore, do not limit myself to the use of my dispenser for dispensing liquid soap.

I claim:

1. A liquid dispenser comprising a reservoir 40 provided with a discharge nozzle at its lower end arranged at an angle to the vertical axis of the reservoir; the said nozzle including a neck adjacent the reservoir having a duct therein elongated vertically throughout the length of the neck, a valve housing adjoining said neck, and a spout adjoining said valve housing having a duct therein elongated vertically throughout the length of the spout; and a pocket valve in said 45 valve housing.

2. A liquid dispenser comprising a reservoir 50 provided with a discharge nozzle at its lower end arranged at an angle to the vertical axis of the reservoir; the said nozzle including a neck adjacent the reservoir having a duct therein elongated vertically throughout the length of the neck, a valve housing adjoining said neck, a spout adjoining said valve housing having a duct therein elongated vertically throughout the length of the spout; and a dispensing valve in said 55 valve housing having a vertically elongated pocket for registration with the vertically elongated duct in said neck and spout.

ALBERT W. LAWNIN.
